UNITED STATES PATENT OFFICE.

FRANK J. PARDINI, OF CARSON CITY, NEVADA.

NON-REFILLABLE BOTTLE.

1,139,900.

Specification of Letters Patent. Patented May 18, 1915.

Application filed October 17, 1914. Serial No. 867,151.

To all whom it may concern:

Be it known that I, FRANK J. PARDINI, a citizen of the United States, residing at Carson City, in the county of Ormsby and State of Nevada, have invented certain new and useful Improvements in Non-Refillable Bottles, of which the following is a specification.

This invention relates to non-refillable bottles, and more particularly to that class of non-refillable bottles in which the neck of the bottle is provided with an enlargement for receiving an expansible stopper that is inserted in the neck of the bottle after the same is filled so as to thereafter permit the contents to be emptied, but prevent refilling of the same.

One of the objects of the invention is to provide a novel form of guard for the expansible stopper which will effectually prevent unscrupulous persons from tampering with the same.

Another object of the invention is to provide means for holding the expansible stopper at all times in its seated position except when the contents of the bottle is being emptied.

A further object of the invention is to provide a bottle of this character which is simple in construction, cheap to manufacture, and efficient and positive in its operation.

With these and other objects in view, the invention consists in the novel features of construction and arrangement of the parts as will be hereinafter more fully described, illustrated in the accompanying drawing and then specifically pointed out in the appended claims.

40 In the drawing:—Figure 1 is a sectional view of a bottle neck showing the improved stopper and guard mounted therein. Fig. 2 is a similar view showing the bottle inverted with the stopper in its unseated position in dotted lines. Fig. 3 is a perspective view of a guard. Fig. 4 is a perspective view of the expansible stopper.

Referring to the drawing by numerals, 1 designates the neck of a bottle that is provided with an enlargement 2 forming a stopper-receiving chamber 3. This enlargement expands abruptly at the top so as to produce a shoulder 4, and from this shoulder the enlargement 3 contacts downwardly into a secondary neck 5 that connects with the body 6 of the bottle.

A substantially cone-shaped stopper 7 preferably comprises a body of compressible and expansible material, such, for instance, as rubber, and is shaped to approximately conform to the shape of the chamber 3 in the neck of the bottle so that having once been inserted in the neck of the bottle it cannot be readily withdrawn.

The stopper 7 comprises a hollow body 65 portion having relatively thin walls in order that the same may be easily inserted within the bottle neck and on the upper wall thereof is formed a plurality of spaced lugs 8. Formed on the lugs 8 and projecting upwardly therefrom is a plurality of flexible members 9 which are normally in engagement with the shoulder 4 to hold the stopper in its seated position. The members 9 are of such size as to have a resistance that will 75 normally hold the stopper seated within the enlargement 3 so as to prevent refilling of the bottle when the same is inverted, but such resistance is overcome by the weight of the liquid within the bottle when the same is 80 inverted to empty the contents thereof, the weight of the liquid overcoming the resistance of the members 9 and causing the same to collapse as shown in Fig. 2 of the drawings in dotted lines.

It is evident from the foregoing that the members 9 can be constructed of practically any flexible material, however rubber would serve very efficiently. Any suitable means 85 can be provided for attaching the members 9 to the lugs 8 such for instance as having the lower extremities of the members 9 embodied therein. It is to be understood however that I am not be limited to this specific construction.

90 The lugs 8 form a limiting means to prevent the stopper from seating on the shoulder 4 when the stopper is in its raised or unseated position.

The neck 1 has a shoulder 10 formed 100 therein a suitable distance above the enlargement 3, and extending upwardly at an angle to the shoulder is a groove or cut-out portion 11, which terminates a suitable distance from the mouth of the neck.

An annular groove is formed in the neck a slight distance above the shoulder 10 and is adapted to extend in a plane at right angles to the cut-out portion 11, and registers with a similar groove in a guard 12 105 110 when the guard is inserted within the neck with its lower face seated on the shoulder 10.

2

A gasket 13 is provided for reception in the groove of the guard and neck, which gasket is in annular form and thickened at a certain point, clearly shown in Fig. 1. The 5 groove mentioned, extends at an angle which is not parallel to the base of the guard, consequently there will be a force exerted at the point where the gasket is lowest, toward the opposite side of the guard; and likewise 10 there will be a force exerted at the point where the gasket is highest, toward the opposite side of the guard, this force tending to force the guard into the position shown in Fig. 1.

15 The guard comprises a hollow body portion, and on its upper angular face is provided with a plurality of discharge openings 14, which extend at an angle to the opening of the bottle neck in order to prevent un- 20 scrupulous persons from tampering with the stopper by inserting a wire or other instrument through said openings.

From the above description taken in connection with the accompanying drawing, the 25 advantages of the construction will be readily appreciated by those skilled in the art to which the invention appertains, and while I have described the principle of operation of the invention, together with the device 30 which I now consider to be the best embodiment thereof, I desire to have it understood that the device shown is merely illustrative, and that such changes may be made as are within the scope of the claims.

35 I claim:—

1. A non-refillable bottle comprising a stopper mounted in an enlarged portion of the neck of said bottle, lugs formed on said stopper and carrying flexible members for 40 engagement with a shoulder formed by said

enlarged portion to hold the stopper normally in engagement with the enlarged portion, a gasket carried within a groove formed in said guard and adapted to engage a groove in the bottle neck, and a cut-out 45 portion in said bottle neck against which the upper end of the guard is adapted to abut to prevent removal of the same.

2. A bottle including an enlarged neck portion, the interior of said enlarged portion tapering toward the upper extremity thereof, lugs formed on the upper face of said stopper, means connecting said lugs and the upper shoulder of said enlarged portion, and a guard disposed in the neck of 55 said bottle as and for the purpose set forth and described.

3. A bottle including an enlarged neck portion, a stopper in said enlarged portion, the interior wall of said enlarged portion 60 tapering outwardly toward the upper portion thereof, a series of lugs carried on the upper face of said stopper, flexible means connecting said lugs and the upper shoulders of said enlarged portion, a guard in the neck 65 of said bottle above said enlarged portion, said guard and said neck being provided with a complementary groove, said groove extending at an angle relative to the base of said guard, a gasket arranged in said groove, 70 a cut-out portion in said neck, for the reception of the upper extremity of said guard, substantially as described.

In testimony whereof I affix my signature in presence of two witnesses.

FRANK J. PARDINI.
